UNITED STATES PATENT OFFICE.

CHARLES T. PRATT, OF FRANKFORT, NEW YORK, ASSIGNOR TO THE PRATT CHUCK COMPANY, OF FRANKFORT, NEW YORK, A CORPORATION OF NEW YORK.

MACHINE FOR FORMING CABLE-ARMOR.

1,098,919.

Specification of Letters Patent. Patented June 2, 1914.

Application filed August 21, 1909. Serial No. 512,985.

To all whom it may concern:

Be it known that I, CHARLES T. PRATT, citizen of the United States, residing at Frankfort, in the county of Herkimer and State of New York, have invented certain new and useful Improvements in Machines for Forming Cable-Armor, of which the following is a specification, reference being had therein to the accompanying drawing.

10 My invention relates to an improved machine for forming cable armor, and I declare that the following is a full, clear, concise and exact description thereof sufficient to enable one skilled in the art to make 15 and use the same, reference being had to the accompanying drawings, in which like reference characters refer to like parts throughout.

The invention has to do with an improved 20 machine for forming a flexible armor for flexible cables, which armor is formed by a spiral winding about such cables of a metallic strip of a form wherein one edge overlaps another when given a spiral form and 25 where allowance is made to place one strand of the spiral against another, so that a given length of the armor may bend freely without parting at the point of overlap. I show a particular form of such armor formed in 30 the manner described of a band or ribbon of metal, which in its cross-section approximates an S-form, as will be seen in the drawings.

I am aware that various means have been 35 proposed for winding such a band about a cable, but in such art the ribbon is customarily given a curved form from edge to edge before it is wound onto the cable or strand to be inclosed in the armor. It is evident 40 that the tendency in coiling one strand upon another in this spiral tends to flatten the cross-sectional corrugation or curve given the metal. It is also evident that there is a strain upon the metal in making this spiral 45 so that frequently it is found necessary to have metal of greater ductility or pliability than it is most desirable for wear.

My invention consists, in one feature thereof, of forming this corrugated band in 50 a spiral by means which greatly reduces the friction on the band as it is given the spiral form, and whereby a band of stiffer metal may be handled and formed. It also provides for the maintaining of the longitudi-

nal curve or corrugation in the ribbon and 55 which is put in the ribbon before it is given the spiral form. This is done by means which act while the spiral is being formed to keep the longitudinal corrugation of the form given or, if anything, to give it a more 60 distinct corrugation, so that I am able not only to handle a stiffer metal, but also insure that the product has the desired corrugation as first given it in the forming mechanism.

In the drawings Figure 1 is a plan view of 65 the machine; Fig. 2 is a side view of the machine; Fig. 3 is a detail view of the spiral forming block, parts broken away; Fig. 4 is a middle vertical view of the block, parts broken away, taken from the side where the 70 metal ribbon enters; Fig. 5 is a cross-sectional view in the opposite direction from Fig. 4 parts broken away; Fig. 6 is a sectional view on the line 6—6 of Fig. 3. Fig. 7 shows a modified construction of race-way, 75 and Fig. 8 shows a modified form of anti-friction members.

Referring to the drawings in detail, 1 represents the table of the machine, with 80 standards 2.

3 and 4 represent standards on the table, having journal-blocks for the shafts 6 and 7. The shafts have mounted at one end wheels 8 and 9 for forming the metal strip which is passed between them. At the opposite end, the shafts are connected with gears 10 and 11. On the lower shaft is mounted a beveled gear-wheel 12 which meshes with the gear wheel 13 mounted on the shaft 14 at the other end of which is 90 mounted pulleys 15 and 16. By the application of power the lower shaft is turned in one direction and the upper shaft in the opposite direction, such directions being determined to turn the forming wheels 8 and 95 9 so as to feed the ribbon therethrough to the forming block. At the end of the shaft 6 is mounted a gear-wheel 18 which meshes with gear-wheel 19 mounted on shaft 20. The shaft is formed with an offset 21 at its 100 outer end, having a stud 22 to carry a reel 23 for the wire to be covered by the armor. It will thus appear, by application of power the two forming wheels or die wheels are rotated to feed material therebetween whereby it is formed and passed to the winding block or die 25 and that said power operates to rotate the reel 23 so that the wire 105

fed into the cable to be formed is turned at the same rate of speed that the cable is formed about it.

The forming block is shown in Figs. 3, 4, 5 and 6, and has mounted at one side thereof a funnel-shaped member 26 (Fig. 1) through which the wire is passed and confined in place to be fed into the cable to be formed about it. This block is shown as made up of two pieces, 30 and 31, adapted to be fitted and secured together and having an opening at 32 into which the ribbon is fed. Portion 30 is formed of any given size and has a bore 24 therethrough of a diameter slightly exceeding that of the cable armor. Around this bore and commencing at a point near the opening for the ribbon into the bore a spiral cutout is made, which in cross-section is about the form of a quarter circle and forms part of the seat for the roller friction balls. This cut-out starts at a point near the surface of the block, as seen at 34 in Fig. 3 and indicated by ball 37, Fig. 4, and slants upwardly as it goes around the bore through the block. The degree of this slant is determined by the pitch to be given to the armor. This cutout is indicated by 35, its formation being such as to leave the edge 36 to operate as a container on that side for the balls 37 which fill the groove. A retainer plate is provided and shown at 40 which has on one face a peripheral ring whose outer edge is of spiral form corresponding to the spiral of the bore 35. It has a cutout at 41 to form a wall and bearing for the balls 37 and is of such a form as to have the edge 42 to operate in conjunction with the aforementioned edge 36 to hold the balls in the groove or track 43 thus made. This retainer plate has a peripheral spiral shoulder at 43 which engages the edge of the ribbon or band and forms it in spirals, the product passing out through the first mentioned bore 24, as seen in Fig. 4. The band 45 is passed into the block with the cross sectional form from edge to edge as seen particularly in Fig. 4, the hollowed portion coming into contact with the balls 37 arranged in the grooves; so as the ribbon 45 is passed around the interior of the block it is guided by the wall 43 of the retainer plate, the hollowed portion 46 of the ribbon bearing on the balls which travel with it around the spiral, these balls taking up the friction which would otherwise retard or prevent the passage of the strip of ribbon, and keeping the ribbon in the form with the curve at 46 as shown. It is the intention that these balls shall have a continuous run-way around and around the bore. In the drawings I show one method of accomplishing this. The upper and larger portion of the block 30 is bored at 48 from the bottom upward and to the right as seen in Fig. 4, and forwardly as indicated by dotted lines

in Fig. 3 to cut into the ball-race and provide a by-pass for the balls, which, when they reach that opening, are deflected into the by-pass, the ball-race being formed only to that point where the by-pass receives the balls. The lower portion 31 of the block has a by-pass 49 which is formed in continuation of the by-pass 48, as seen in Fig. 4. The by-pass 48 in the main or larger portion of the block has such an angle as to clear the edge of the ribbon when it is fed in. The by-pass 49 in the lower portion is formed to carry the balls backward to the starting point where they pass up the inclined bottom in the smaller portion of the block and onto the inclined bottom of the track in the larger portion where they are again engaged by the ribbon and with it pass around the spiral. This lower block is secured to the main portion by bolts 50 and the retainer plate is secured to both blocks by the screws 51, while the whole block is held by bolts 52. In Fig. 7 I show a different return track 53 for the balls, which starts from about the same point already shown, but instead of going downward and across goes upward and around, being cut into the block in proper direction to bring the balls again to the starting point.

As one modification of the device I show a form in which I use a series of friction wheels 55 instead of the friction balls. These have studs 56 (by which they are carried in the block) in holes 57, each wheel being given a tilt corresponding to the pitch. The main features of the construction are the same, the spiral rim of the retainer plate having a like shoulder as already shown, to guide the ribbon through the forming block. A plurality of wheels are shown by 55, the periphery of each of which is given a form similar to that of the cross section of the ribbon in contact with it, each wheel taking up the friction and at the same time assisting in the forming of the finished product 60 with its longitudinal corrugation, formed in a flexible cable about wires 61.

It will be understood that the forming block may be made of a single piece or built up, being shown as the latter for convenience in illustration and that in the form shown in Figs. 7 and 8 a counterpart is presupposed, corresponding with the features shown. It will also be within the mechanic's skill to provide a duplication of reel mechanisms for a gang of wires, if desired.

It will be apparent that various modifications may be made in the application and principle disclosed, and I have given but one illustration with certain modifications.

Having described my invention, what I claim as new and desire to secure by Letters Patent, is:

1. In a machine for forming cable armor, forming wheels adapted to give a certain

curvature in cross section to a metallic strip passed therebetween, a die adapted to receive said metallic strip as same emerges from said wheels, a spiral passageway in said die, an endless passageway for ball bearings, whereby said ball bearings in said passageway may contact with said metallic strip as same is passed through said first mentioned passageway in said die and give said metallic strip 5 an increased curvature in cross section, substantially as described.

2. In a machine of the character described, a forming block, a bore transverse said block for the passage of wires, a spiral passageway 15 in said block for the passage of a metallic band, whereby to armor said wires, a shoulder forming one boundary of said spiral passageway, whereby to constitute a guide for said armor strip, and anti-friction balls 20 in said passageway, whereby to maintain a given configuration in said armor strip, substantially as described.

3. In a machine of the character described, the combination of a block, a bore transverse said block for the passage of wires, a spiral passageway in said block for the passage of a metallic band, whereby to armor 25 said wires, a shoulder forming one boundary of said spiral passageway to constitute a guide for said armor band, anti-friction balls 30 in said passageway whereby to maintain a given configuration in said armor band, and means for twisting said wires, substantially as described.

35 4. In an armor machine of the character described, the combination of forming

wheels, adapted to give a certain curvature in cross section to a metallic strip passed therebetween, a die adapted to receive said metallic strip as same emerges from said 40 wheels, a spiral passageway in said die, an endless passageway in said die for ball bearings, whereby said ball bearings may contact with said metallic strip and give same a given degree of curvature in cross-section. 45

5. In an armor machine of the character described, the combination of forming wheels, adapted to give a certain curvature in cross section to a metallic band, a die adapted to receive said metallic strip as the 50 same emerges from between said forming wheels, a spiral passageway in said die, whereby to coil said band about a plurality of wires, and an endless passageway leading into and out of said spiral passageway for 55 the passage of ball bearings adapted to maintain the given curvature in cross section to said metallic band, substantially as described.

6. In a device of the character described, 60 a block, spirally arranged grooves therein for the passage of a strip to be coiled, a passageway in said block and antifriction members in said passageway, bearing on said strip and giving the same a given form in 65 cross-section.

In testimony whereof I hereunto affix my signature in the presence of two witnesses.

CHARLES T. PRATT.
